UNITED STATES PATENT OFFICE.

ERNST A. WULLENWEBER, OF MELROSE, MASSACHUSETTS, ASSIGNOR TO HOOD RUBBER COMPANY, OF WATERTOWN, MASSACHUSETTS, A CORPORATION OF MASSACHUSETTS.

DESIGN FOR A TIRE.

Application filed May 25, 1928. Serial No. 26,857. Term of patent 3½ years.

To all whom it may concern:

Be it known that I, ERNST A. WULLENWEBER, a citizen of the United States, residing at Melrose, in the county of Middlesex and State of Massachusetts, have invented a new, original, and ornamental Design for Tire, of which the following is a specification, reference being had to the accompanying drawing, forming part thereof.

Referring to the drawings:

Figure 1 is a plan view of a portion of a tire embodying my new design.

Fig. 2 is a sectional elevation taken on line 2—2, Fig. 1.

Fig. 3 is a fragmentary sectional elevation taken on line 3—3, Fig. 1.

I claim:

The ornamental design for a tire, as shown.

ERNST A. WULLENWEBER.
